UNITED STATES PATENT OFFICE.

ELDRED GILBERT GRAVES, OF NORMAL, AND OTIS KENT WELLS, OF BLOOMINGTON,
ILLINOIS.

COMBINED CRUSHER AND STOKER.

1,369,237.

Specification of Letters Patent. Patented Feb. 22, 1921.

Application filed October 6, 1919. Serial No. 328,623.

To all whom it may concern:

Be it known that we, ELDRED G. GRAVES and OTIS K. WELLS, citizens of the United States, residing at Normal and Bloomington, in the county of McLean and State of Illinois, have invented certain new and useful Improvements in Combined Crushers and Stokers; and we do declare the following to be a full, clear, and exact description of the invention, such as will enable others skilled in the art to which it appertains to make and use the same.

This invention relates to stokers, and more specifically to an improved combined coal-crusher and stoker.

One object of the invention is to provide an improved device of this character which is comparatively simple, and inexpensive, and which crushes the large lumps of coal while the coal is being conveyed toward the fire-box into which it is to be fed, thereby enabling ungraded coal to be fed without incurring the unsatisfactory effects of feeding the large lumps of coal into the fire-box.

Another object is to provide an improved stoker of this character which is attachable to any ordinary locomotive without the necessity of making very material or expensive preliminary changes to the locomotive's fire-box and tender.

Other objects and advantages may become apparent to persons who read the following details of description in connection with the accompanying drawings in which:

Figure 1 is a view, partly in side elevation and partly in vertical section, illustrating the relation of the portions which are supported by the fire-box and the tender respectively.

Fig. 2 is a front end elevation illustrating the connection of the conveyer with the flexible tubular structure which is carried by the fire-box and conducts coal from the conveyer to the fire-box.

Fig. 3 is a transverse sectional view along the line 3-3 of Fig. 1.

Fig. 4 is a sectional view along the line 4-4 of Fig. 1.

Referring to these drawings in detail, in which similar reference characters correspond with similar parts throughout the several views, and in which a fire-box of any ordinary construction is designated by the numeral 1, the numeral 2 designating a bin

or locomotive tender of ordinary construction.

Our improved device comprises a conveyer tube 3, a hopper 4 in open communication with the conveyer tube, a crushing device 5 at the junction of the tube 3 and hopper 4, a rotary conveyer member 6, a wheel 7 on the upper end of the conveyer member 6, a driving member 8 meshing with the wheel 7, and a spout or outlet 9 which communicates with the upper end of the conveyer tube 3. The elements 3 to 9 inclusive are carried by the bin 2, and any appropriate means such as a bracket 10, for instance, may be employed for securing the conveyer tube in fixed position with relation to the bin 2. The conveyer member 6 is preferably of the worm type, having a helical plate 11 extending approximately from end to end. The hopper 4 is in effect a continuation of the conveyer tube 3, and the crusher member 5 is formed or secured in rigid relation with the hopper and conveyer tube. By referring to Fig. 3 in connection with Fig. 1, it will be seen that the crusher member 5 includes an arcuate series of bars or ribs 12 which converge from front to rear and are also in convergent relation to the axis of the rotary conveyer member 6. The conveyer member extends from the conveyer tube 3 under the crusher member 5 into the hopper 4, and therefore, when the member 6 is rotated in the proper direction while coal is in the hopper 4, such coal will be fed from the hopper into the tube and through the latter into the spout 9.

The coal, in passing from the hopper to the conveyer tube, is guided into the latter by the converging arrangement of bars or ribs 12, and the large lumps are crushed by the correlated or combined action of the conveyer member 6 and the crushing device 5. In practice, the bin or tender 2 will be filled or supplied with coal, and the same passes by gravity into the hopper 4.

For the purpose of compensating for the varying relative positions of the tender and fire-box of a locomotive, the spout 9 is removably secured by any appropriate means to the upper joint 13 of one or more flexible tubes or conduits 14. The means illustrated for connecting the members 9 and 13 may consist of a pair of rollers 9^a journaled on the lower end of the member 9 and each engaged with a bayonet-slot 13^b of the mem-

ber 13. These conduits may be of any appropriate construction, but preferably consist respectively of a plurality of frusto-conical-tube sections which are movably connected to one another in such relation that the conduit may be flexed laterally in all directions, and may be lengthened and shortened to a limited extent. In the present embodiment of the invention, two of the flexible conduits 14 are disclosed, their upper ends being united through the medium of a Y-connection 13^a which forms an element of the member 13. The deflector blade 15 is pivotally mounted at 16 at the lower portion of the member 13, and a lever or crank 17 is provided for turning the member 15 either rightward or leftward so as to prevent the flow of coal through either elected one of the flexible tubes 14. A segment 18 is mounted on the member 13, and a bolt or other appropriate means 19 may be provided on the crank 17 for securing the latter to the segment 18 in any adjusted position.

Feed nozzles 20 are secured to the fire-box 1 by any appropriate means, as indicated at 21, for instance, and these feed nozzles support the flexible tubes 14, being movably secured thereto by any appropriate means.

It will be seen, therefore, that the elements 3 to 9 inclusive are supported independently of the fire-box, and that the elements 13 to 21 inclusive are supported independently of the tender or coal-bin, and therefore, any tender provided with a conveyer of this character may be quickly and easily connected in stoking relation to any fire-box equipped with a feed nozzle 20 and the elements supported thereby. It will be seen, moreover, that a device of this character may be very quickly and easily attached to a locomotive of any ordinary type with comparative ease and facility and without changing the fire-box and cylinder to any considerable extent.

In order that the coal shall not clog or accumulate in the nozzle 20, steam-jets or nozzles 22 may be provided, so that a blast of steam may not only dislodge the coal from the nozzle 20 and carry this coal into the fire-box, but will also aid combustion in a manner which is known to those who are familiar with the art. A door 23 may be provided at the rear end of the nozzle, so that a poker or other implement may be employed for dislodging coal which cannot be dislodged by the steam-jet 22.

Attention is directed to the fact that the pipe 3 and its discharge spout 9, are carried rigidly by the tender, and the pipes 14 and 60 the Y-coupling 13^a are carried totally by the locomotive, being detachably connected with said spout by means of the bayonet slots 13^b and the rollers 9^a. These parts not only afford a detachable connection between the 65 two units of the stoker, but they afford a swivel connection between them which comes into play when relative turning of the locomotive and tender takes place. When the tender and locomotive are to be uncoupled, 70 this combined swivel and detachable connection is disengaged and the several sections of the pipes 14 then nest snugly within each other into a compact formation which occupies but little space. 75

Although we have described this embodiment of our invention very specifically, it is not intended to limit this invention to these exact details of construction and arrangement, but changes may be made within the 80 scope of the inventive ideas as implied and claimed.

What we claim as our invention is:

1. The combination with a locomotive and its tender, of a forwardly inclined coal conveying pipe carried rigidly by the tender and provided at its front end with a depending discharge spout, an inverted Y-coupling having a combined detachable and swivel connection with said spout, and a 90 pair of fuel feed pipes connected at their upper ends with the branches of said Y-coupling and carrying said coupling, said fuel feed pipes being carried by the locomotive, diverging downwardly to the fire-box thereof, and being formed of loosely connected interfitting sections designed to nest within each other when said Y-coupling is detached from said discharge spout to permit uncoupling of the locomotive and 100 tender. 95

2. A structure as specified in claim 1, said combined detachable and swivel connection consisting of bayonet slots in said Y-coupling having horizontally elongated inner 105 ends, and rollers on said discharge spout received in said slots and adapted to travel along said horizontally elongated ends thereof when the locomotive and tender turn relatively. 110

In testimony whereof we have hereunto set our hands.

ELDRED GILBERT GRAVES.
OTIS KENT WELLS.
